US0D1058542S

(12) **United States Design Patent** (10) **Patent No.:** **US D1,058,542 S**
(45) **Date of Patent:** **** Jan. 21, 2025**

(54) **CAR ANTENNA**

(71) Applicant: **Shenzhen Early Bus Supply Chain Management Co., Ltd.**, Shenzhen (CN)

(72) Inventor: **Liping Zhang**, Shenzhen (CN)

(73) Assignee: **Shenzhen Early Bus Supply Chain Management Co., Ltd.**, Shenzhen (CN)

(**) Term: **15 Years**

(21) Appl. No.: **29/856,408**

(22) Filed: **Oct. 13, 2022**

(30) **Foreign Application Priority Data**

Sep. 29, 2022 (CN) 202230649434.X

(51) **LOC (15) Cl.** **14-03**

(52) **U.S. Cl.**

USPC **D14/230**

(58) **Field of Classification Search**

USPC D14/230, 231-240, 299, 258, 138, 238.1, D14/243, 217; D12/32, 43; D9/232; D6/300, 303, 310, 311; D4/358; D13/182; D23/264, 367

(57) **CLAIM**

The ornamental design for a car antenna, as shown and described.

DESCRIPTION

FIG. 1 is a front perspective view of a car antenna, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is the enlarged plan of its top surface; and,

FIG. 8 is the enlarged plan of its bottom surface.

The broken lines in the drawings illustrate the portions of the car antenna, which form no part of the claimed design.

1 Claim, 8 Drawing Sheets
